ATTORNEY

UNITED STATES PATENT OFFICE.

CHARLES SAMUEL FRANKLIN, OF BUCKHURST HILL, ENGLAND, ASSIGNOR TO RADIO CORPORATION OF AMERICA, A CORPORATION OF DELAWARE.

AERIAL SYSTEM EMPLOYED IN WIRELESS TELEGRAPHY AND TELEPHONY.

1,368,622.

Specification of Letters Patent. Patented Feb. 15, 1921.

Application filed August 26, 1920. Serial No. 406,173.

To all whom it may concern:

Be it known that I, CHARLES SAMUEL FRANKLIN, a subject of the King of Great Britain, and resident of St. Michaels, Westbury Lane, Buckhurst Hill, in the county of Essex, England, have invented new and useful Improvements in Aerial Systems Employed in Wireless Telegraphy and Telephony, of which the following is a specification.

When a system of spaced aerials is employed for directional working in wireless telegraphy, it is very desirable that the tuning of all the aerials should be under control at one central place.

This has been done by bringing a pair of parallel wires connected to each aerial to the central place and locating the necessary tuning inductances and condensers there.

When however the wires are a considerable fraction of a wave length it is found that although the aerial can be tuned by adjusting the condenser or inductance, there is a strong tendency for the aerial and wires to oscillate as a long horizontal aerial and so directional properties of the aerial are impaired.

According to this invention, instead of connecting the horizontal parallel wires directly to the aerial, I connect the aerial to one winding of a transformer, and I connect the wires to the other winding.

Preferably an earthed shield is interposed between the windings of the transformer.

A similar transformer may be connected to the other end of the wires, one winding being connected to the wires and the other winding to the tuning elements. Such transformers may also be interposed at intermediate places along the connecting wires.

The invention is illustrated in the drawing. A is a frame aerial, B the connecting wires, I and C the tuning inductance and condenser near to the receiver R. 1, 2, 3, 45 are transformers having an earthed shield interposing between the two windings of each.

I have found that such an arrangement enables aerial A to be tuned by means of the tuning elements I and C located a considerable fraction of a wave length from A, and at the same time the aerial A and wires B are prevented from oscillating as a long horizontal aerial.

The transformers 1, 2 and 3 are preferably wound to have very small leakage and small capacity between the windings and between the windings and the earth screen.

The inductance of each transformer winding should be high compared with the inductance of the aerial A.

The invention is illustrated as applied to a frame aerial, but it can be applied to any type of aerial.

What I claim is:

1. At a wireless station, the combination of an aerial, a primary winding therein, a secondary winding closely coupled to the primary winding whereby the leakage coefficient is minimized, a line circuit connected to the secondary winding and means connected in the line circuit for tuning the aerial system.

2. At a wireless station the combination of an aerial, a primary winding therein, a secondary winding closely coupled to the primary winding whereby the leakage coefficient is minimized, a line circuit connected to the secondary winding and means for tuning the aerial system connected in the line circuit and spaced a considerable fraction of a wave length from the aerial.

3. At a wireless station, the combination of an aerial, a primary winding therein, a secondary winding, an earthed shield between the windings, lines connected to this secondary winding and means connected to the lines for tuning the aerial system.

4. At a wireless station, the combination of an aerial, a primary winding therein, a secondary winding, an earthed shield between the windings, lines connected to the secondary winding and means for tuning the aerial system connected to the lines and spaced a considerable fraction of a wave length from the aerial.

5. At a wireless station the combination of an aerial, a primary winding therein, a secondary winding closely coupled to the primary winding whereby the leakage coefficient is minimized, a line circuit connected to the secondary winding, a receiving circuit coupled to the line circuit and spaced a considerable fraction of a wave length from the aerial and means for tuning the aerial system connected in the line circuit in proximity to the receiving circuit.

6. At a wireless station, the combination

- of an aerial, tuning means situated at a distance therefrom, lines extending between the aerial and tuning means, a transformer between the aerial and lines and an additional 5 transformer having its primary and secondary in the lines interposed between the aerial and tuning means.
7. At a wireless station, the combination of an aerial, tuning means situated at a distance therefrom, lines extending between the 10 aerial and the tuning means and a plurality of transformers having their primaries and secondaries in the lines interposed between the aerial and the tuning means.
- 15 8. At a wireless station, the combination of an aerial, tuning means situated at a distance therefrom, lines extending between the aerial and the tuning means, a plurality of transformers interposed between the aerial 20 and the tuning means, and an earthed shield

between the two windings of each transformer.

9. At a wireless station, the combination of an aerial, a primary winding therein, a secondary winding of high inductance as 25 compared with the inductance of said aerial, said secondary winding being closely coupled to the primary winding whereby the leakage coefficient is minimized, a line circuit connected to the secondary winding and 30 means connected in the line circuit for tuning the aerial system.

In testimony that I claim the foregoing as my invention I have signed my name this thirtieth day of July, 1920.

CHARLES SAMUEL FRANKLIN.
